UNITED STATES PATENT OFFICE.

LUCY GRANT UNMACK, OF LOS ANGELES, CALIFORNIA.

DESIGN FOR A CANDLESTICK.

60,480.

Specification for Design.

Patented Feb. 21, 1922.

Application filed May 5, 1921. Serial No. 467,215. Term of patent 3½ years.

To all whom it may concern:

Be it known that I, LUCY GRANT UNMACK, a citizen of the United States, residing at Los Angeles, in the county of Los Angeles and State of California, have invented a new, original, and ornamental Design for Candlestick, of which the following is a specification, reference being had to the accompanying drawing, in which:

The characteristic feature of my design resides in forming a candle stick having the figure of a doll garbed in Japanese costume.

I claim:

The ornamental design for a candlestick substantially as shown and described.

LUCY GRANT UNMACK.
